(57) CLAIM

The ornamental design for a combined scarf and pillow, as shown and described.

DESCRIPTION

FIG. 1 is a top perspective view of a combined scarf and pillow showing my new design;

FIG. 2 is a top plan view thereof;

FIG. 3 is a bottom plan view thereof;

FIG. 4 is the right side elevational view thereof;

FIG. 5 is the left side elevational view thereof;

FIG. 6 is the right end view thereof;

FIG. 7 is the left end view thereof; and,

FIG. 8 is another top perspective view thereof shown in an in use configuration.

The broken line showing of the scarf tassels in FIGS. 1-8 is for illustrative purposes only and forms no part of the claimed design. The broken line showing of the human figure in FIG. 8 is for illustrative purposes only and forms no part of the claimed design.
